UNITED STATES PATENT OFFICE

FRANK COATES, OF CLEADON, ENGLAND, ASSIGNOR TO A. REYROLLE & COMPANY LIMITED, OF HEBBURN-ON-TYNE, ENGLAND, A COMPANY OF GREAT BRITAIN

ELECTRIC COUPLING

Application filed January 3, 1929, Serial No. 329,991, and in Great Britain March 6, 1928.

This invention relates to electric couplings of the metal-clad orifice type in which a conductor usually terminating in a socket is surrounded by a condenser contained within the orifice of a metal casing. Such couplings are often used, for instance, in metal-clad switchgear of the draw-out type.

The condenser portion of such a coupling is generally made of alternate layers of impregnated paper or like insulating material and thin metal sheet or foil, and the insulating material is to some extent hygroscopic. There is, therefore, sometimes a tendency for moisture to collect and for the dielectric strength of the arrangement to be reduced.

To obviate this a metal-clad orifice coupling according to the present invention is provided with an inner liner of porcelain or like impervious insulating material which makes a closed joint with the outer end or mouth of the metal casing and forms an enclosing inner cover for the condenser which is contained in the annular space between the liner and the metal casing.

Conveniently this inner liner is bell-shaped with a hollow neck or a hole at its inner end where it makes a joint with a central conductor which passes through it and terminates in a socket. The outer end of the liner may be flared or flanged and may be clamped or otherwise secured to the mouth of the casing with which it makes a closed joint.

Preferably there is inside the casing a disc or spider forming a support for the condenser which is held clear of the casing and also of the insulating inner liner. The space around the condenser may be wholly or partially filled by compound or by oil or like insulating fluid.

In the accompanying drawings,

Figure 1 is a central section of one construction of electric coupling according to this invention, and

Figure 2 is a similar view of a modified form.

In the construction shown in Figure 1 a central conductor A terminating in a socket A¹ carries a spider B upon which a condenser C is supported the whole being with-

in a metal casing D which may be mounted on or form part of metal-clad switchgear.

A bell-shaped liner E of porcelain or like impervious insulating material having a hole at its inner end makes a joint with the inwardly projecting end of the central conductor A, this joint being rendered oil-tight by means of oil-resisting washers F. The outer end of the liner E is flanged and secured by means of studs G to the mouth of the metal casing D so as to make a closed joint therewith, oil-resisting washers H ensuring that the joint is oil-tight. The spider B holds the condenser C in the annular space between the casing D and the liner E so as to be clear of both the casing and the liner and the space thus provided around the condenser C is partially or wholly filled with oil or other insulating fluid or compound, the spider B having holes B¹ for its passage.

In the modified construction, illustrated in Figure 2, which is particularly adapted to be filled with insulating compound, the inner liner E¹ has a neck at its inner end where it is secured to the inwardly projecting portion or socket end of the central conductor A² by means of cement J. The outer edge of the liner E¹ is flared and is secured to the mouth of the metal casing D¹ by means of cement K. The space around the condenser C is wholly or partially filled with insulating compound.

What I claim as my invention and desire to secure by Letters Patent is:—

1. A metal-clad electric coupling of the condenser orifice type comprising a conductor, a tubular condenser supported around said conductor, a metal casing around said condenser, and an inner member of impervious insulating material separate from the condenser, said inner member being attached to said conductor and forming a closed joint with the outer end or mouth of said metal casing.

2. A metal-clad electric coupling of the condenser orifice type comprising a conductor, a tubular condenser supported around said conductor, a metal casing around said condenser, and a bell-shaped inner member of impervious insulating material having at one end a hole through which the conductor

passes, said inner member being flanged at the other end where it forms a closed joint with the outer end or mouth of said metal casing.

- 5 3. A metal-clad electric coupling of the condenser orifice type comprising a conductor, a tubular condenser supported around said conductor, a metal casing around said condenser, an inner member of impervious insulating material attached to said conductor and forming a closed joint with the outer end or mouth of said metal casing, and means attached to said conductor for supporting the tubular condenser clear of the casing and the
10 inner member, thus providing a space adapted to contain an insulating medium.

15 In testimony whereof I have signed my name to this specification.

FRANK COATES.
